UNITED STATES PATENT OFFICE.

FREDERICK W. HEDGELAND, OF CHICAGO, ILLINOIS.

MECHANISM FOR DRIVING MUSIC-SHEETS OF SELF-PLAYING INSTRUMENTS.

SPECIFICATION forming part of Letters Patent No. 629,361, dated July 25, 1899.

Application filed May 26, 1898. Serial No. 681,807. (No model.)

To all whom it may concern:

Be it known that I, FREDERICK W. HEDGELAND, a citizen of the United States, residing in Chicago, in the county of Cook and State 5 of Illinois, have invented a new and useful Improvement in Mechanism for Driving the Music-Sheets of Self-Playing Instruments, of which the following is a specification.

This invention relates to the construction 10 of friction mechanism for transmitting motion from the motor to the music-roll of self-playing instruments.

The invention is an improvement upon the construction set forth in my application Serial No. 673,585; and its object is to simplify and improve some of the features of my said prior invention.

The nature of the invention will appear from the description which I give below.

20 In the accompanying drawings I show, at Figure 1, a plan of the invention; at Fig. 2, an elevation thereof; at Fig. 3, a partial elevation at right angles to that given in Fig. 2, and at Fig. 4 a detailed section.

25 In said drawings, A represents the pulley attached to the motor of the instrument, or it may be a pulley receiving power in some suitable way from the motor. This pulley drives the belt B, which passes first over the 30 idler C, under the pulley D, over the idler E, under the main pulley F, and thence over the idler G back to the pulley A. I employ this system of belting in order to enable the invention to be used with motors positioned 35 vertically, that position being very desirable, because it allows all the power-pneumatics in that class of motors in which the pneumatics are arranged around the axis of the driven pulley to stand in the position in which they

40 will all be affected alike by gravity. The pulley F is mounted upon the same shaft with the friction-cone H, and both are supported by bearing-blocks I J from a movable base K. This base is preferably in one piece with 45 the arm K' and is pivoted at A². The cone, except while the rewinding is being done, is in contact with a friction-wheel L upon the shaft L', the base K being normally pressed so as to carry the cone against the wheel by 50 a spring M. The shaft L' may be permanently connected to the take-up roll O, as it does not need to be detached therefrom during rewinding. The hub of friction-wheel L

is extended laterally upon one side, as shown at L², and is movable along the shaft, being 55 splined thereto, so that the shaft must rotate with it, and said laterally-extended end of the hub is provided with collars L³, between which the arm L⁴, attached to a rocking shaft or bar L⁵, enters. The bar L⁵ is intended to 60 be rocked by the operator, and through it he shifts the friction-wheel to any point desired along the surface of the cone which will enable him to obtain the speed desired for the music-sheet.

65 The cone is moved away from the friction-wheel so as to destroy operative contact between the two whenever it is desired to rewind the music-sheet by means of the stop-rod N, which is joined to the base K. The operator 70 retains the cone in this changed position during the rewinding operation, as otherwise the spring M would act to carry it back against the friction-wheel. When the operator thus moves the cone away from the friction-wheel, 75 he also establishes an operative relation between the shaft D', carrying the pulley D, and the music-roll, (shown at P.) This is done by moving said shaft longitudinally, so as to cause a clutching engagement between it and 80 the sleeve P', mounted upon the journal P², which enters and supports the music-roll, the end of the sleeve which receives the shaft being slotted, as at P³, and said shaft D' being provided with one or more wings or projections D², adapted to enter said slots. Inside of the sleeve P' is a loose disk P⁴ and a spring P⁵, confined between the journal P² and said disk. This spring P⁵ is compressed 85 when the clutching relation is established, 90 and at other times is expanded so as to keep the disk P⁴ against its seat. It tends to facilitate and render certain the disengagement of the parts of the clutch when the rewinding is complete. The shaft D' is driven 95 in the opposite direction from shaft L' and is supported at one end in the sleeve P' and at the other end by a stationary standard D³. A base-block D⁴ is pivotally united to the arm K' at D⁵, so that it moves with the 100 arm K' when the operator shifts the cone away from the friction-wheel. The shaft D' moves with the base-block by reason of the springs D⁶ and D⁷, which project upwardly from the block, one standing opposite the 105 end of the shaft and the other in position

where it will bear against the side of the pulley D, as plainly illustrated. The movement received from the arm K' carries the base-block and shaft D in the direction which will 5 establish the clutching connection between the shaft and the sleeve P', and when the arm K' moves back to its normal position the spring D⁷ tends to release the clutching engagement. From the description thus given 10 it will be seen that the music-roll is free to turn in unison with the take-up roll while the instrument is playing and that the shifting of the cone so as to destroy its contact with the friction-wheel not only results in a temporary cessation of such contact, but also 15 causes the closing of the clutch and the operation of the music-roll in the rewinding. The idler E is mounted on the end of a swinging arm E', the free end of which is impelled upward by a spring E², so as to keep the belt constantly and uniformly tight. The upright E³ supports said arm and also a cross-bar E⁴, upon which the idlers C and G may be 20 mounted. A portion of the tracker-range is shown at O'. The rewinding is thus accomplished without either a cessation of movement by the motor or any change in the direction of its rotation.

I claim—

- 30 1. The combination with the motor and rolls carrying the music-sheet, of a friction-wheel for driving the take-up roll, a friction-cone belted to the motor and normally in contact with said wheel, and also movable from its normal position to destroy such contact, and a pulley actuated by the belt connecting the motor and cone and having a clutching connection with the music-roll, substantially as specified.
- 35 2. The combination with the motor and rolls carrying the music-sheet, of a friction-wheel for driving the take-up roll, a friction-cone belted to the motor and normally in contact with said wheel, and also movable from its normal position to destroy such contact, and a pulley actuated by the belt connecting the motor and cone and having a clutching connection with the music-roll, substantially as specified.
- 40 3. The combination with the motor and rolls carrying the music-sheet, of a friction-wheel for driving the take-up roll, a friction-cone belted to the motor and normally in contact with said wheel, and also movable from its normal position to destroy such contact, and a pulley actuated by the belt connecting the motor and cone and provided with means acting to carry it into clutching engagement with the music-roll, substantially as specified.
- 45 4. The combination with the motor and rolls carrying the music-sheet, of a friction-wheel for driving the take-up roll, a friction-cone belted to the motor and normally in contact with said wheel, and also movable from its normal position to destroy such contact, and a pulley actuated by the belt connecting the motor and cone and provided with means connected to the cone-support and movable therewith, and acting to establish operative engagement between the pulley and the music-roll, substantially as specified.
- 50 5. The combination with the motor and rolls controlling the music-sheet, of variable-speed friction mechanism consisting of separable members transmitting power to the take-up roll, and a pulley D actuated by the belt carrying power from the motor to the fric-

tion mechanism, and adapted to be clutched to the music-roll, substantially as specified.

5. The combination with the motor and 70 rolls controlling the music-sheet, of variable-speed friction mechanism consisting of separable members transmitting power to the take-up roll, and a pulley D continuously driven in one direction, and idly rotating 75 while the friction members are in contact, but movable to establish a clutching connection with the music-roll when the friction members are separated, substantially as specified.

6. The combination with the motor, the 80 rolls controlling the music-sheet, and the variable-speed-producing friction mechanism for driving the take-up roll, said friction mechanism embracing separable members, of a pulley continuously driven at a uniform speed 85 directly from the motor in one direction, and movable in position to establish a clutching connection with the music-roll, and means whereby the operator may simultaneously 90 separate the members of the friction mechanism and shift said pulley, substantially as specified.

7. The combination with the motor, and the 95 rolls controlling the music-sheet, of the friction cone and wheel and pulley D, the former belted to the motor by a belt also actuating a pulley D, said friction cone and wheel being separable, and said pulley being movable into clutching engagement with the music-roll, substantially as specified.

8. The combination with the motor, and the 100 rolls controlling the music-sheet, of the friction cone and wheel and pulley D, the cone and the pulley being both driven directly from the motor, said cone and wheel being 105 separable and said pulley being movable into clutching engagement with the music-roll, and means operable at will for separating the cone and wheel and shifting the pulley, substantially as specified.

9. The combination with the motor and 110 music-rolls, of a variable-speed friction mechanism, comprising separable friction members for driving one of the rolls, a clutching-pulley for driving the other roll, an idler E 115 interposed between said mechanism and said pulley, and a single belt actuating both the friction mechanism and said pulley, and passing over said idler, substantially as specified.

10. The combination with the motor and 120 music-rolls, of a variable-speed friction mechanism, comprising separable friction members for driving one of the rolls, a clutching-pulley for driving the other roll, an idler E 125 interposed between said mechanism and said pulley, and a single belt actuating both the friction mechanism and said pulley, and passing over said idler, said idler also acting as a take-up, substantially as specified.
